UNITED STATES PATENT OFFICE

2,100,441

DRIER

Chester W. Greene, Lynn, Mass., assignor to
United Shoe Machinery Corporation, Paterson,
N. J., a corporation of New Jersey

Application September 20, 1935, Serial No. 41,434

7 Claims. (Cl. 198—24)

This invention relates to driers and is herein illustrated as embodied in a machine for drying soles which have been coated with cement.

In the manufacture of shoes the soles of which are attached by cement, it is customary to coat the attaching faces of the soles with a cement, commonly a pyroxylin cement, to allow the cement to dry and then, just prior to attaching the soles to shoes, to activate the cement by treating it with a solvent. The illustrated machine is particularly adapted to receive freshly cemented soles one by one, to maintain them in separated relation for an interval during which they are dried, and finally to arrange the dried soles in a stack.

According to one feature of the invention, there is provided a conveyor having article carriers, means for operating the conveyor, and feeding means operated in timed relation to the operation of the conveyor for feeding an article into the path of the article carriers at one locality and for feeding another article out of the path of the carriers at another locality. In the illustrated machine, the conveyor has upwardly and downwardly extending runs provided with sole carriers, a freshly cemented wet sole being fed into the path of the carriers at the bottom of the upwardly extending run while a dry sole is simultaneously fed out of the path of the carriers at the bottom of the downwardly extending run and is added to the bottom of a stack.

In order to ensure that the articles, whatever their size, shall be properly fed into the path of movement of the article carriers and shall also be properly fed into the path of movement of the stacking member, the feed members, in accordance with another feature of the invention, are operated through yielding actuating mechanism in such manner as to feed all the articles, whatever their size, against abutments and hold them there until they are carried away either by the article carriers of the conveyor or by the stacking member.

These and other features of the invention, including certain details of construction and combinations of parts, will be described as embodied in an illustrated machine and pointed out in the appended claims.

Referring to the accompanying drawings,

Fig. 1 is a side elevation of a machine in which the invention is embodied, the top of the machine being broken off and the parts of the machine being shown in the positions in which they come to rest;

Fig. 1^a is a detail principally in longitudinal section of the clutch;

Fig. 2 is a section of the line II—II of Fig. 3, the top of the machine being broken off and the parts of the machine being shown in the positions they occupy at the end of the forward stroke of the feed members;

Fig. 3 is a rear elevation of the machine, certain parts of the machine between the extreme upper end and the base having been removed.

The machine comprises a base 9 in a socket in the upper part of which is threaded the lower end of an upwardly extending rod 11 (Fig. 3) the upper end of which is threaded into the bottom of a sprocket support 13 having rotatable 15 therein a horizontal shaft 14 carrying at its opposite ends two sprockets the hubs of which are indicated at 15, 16. A nut 17 threaded on the upper part of the rod 11 engages the under side of the sprocket support. Four stay rods 18 having headed upper ends extend through bores in lugs on the sprocket support 13, their lower ends extending through bores in lugs 19 on the base and having nuts 21 threaded on their lower extremities. With this construction, the sprocket support 13 may be adjusted heightwise and firmly held in adjusted elevated position. Over the sprocket 15 and two sprockets 23 (Fig. 2) rotatably mounted in the base of the machine extends a chain 25; and over the sprocket 16 (Fig. 3) 20 and two sprockets (not shown) which are aligned respectively with the two sprockets 23 and like them are rotatably mounted in the base of the machine, extends a second chain 29. These two chains which are aligned with each other have 25 fastened to certain of their parts sole-supporting fingers 31 (Figs. 1 and 2). Any given finger on any chain is at all times in the same plane as a corresponding finger on the other chain, and a pair of such fingers when in certain parts of the paths of the chains form a shelf or carrier for an article such as a sole which has been thrust upon them. The chains are driven intermittently in unison by mechanism to be described later, the extent of each 30 movement being equal to the distance between one carrier (composed of two fingers) and an adjacent carrier. There is thus provided a sole conveyor having a generally triangular outline 35 when viewed from the side, as in Figs. 1 and 2, having at the left an upwardly-traveling run, at the right a downwardly-traveling run, and at the bottom a substantially horizontal run. The soles 100 are fed one by one to a carrier at the 40 base of the upwardly-traveling left-hand run,

45

45

50

55

55

are carried up over the sprockets 15, 16 and then down to the base of the right-hand run where they are removed one by one and stacked in a manner presently to be described. The movement of the conveyor is comparatively slow so that the soles have time to dry between the time they are placed on a carrier of the conveyor and the time they are removed therefrom. A rotary fan 39 (Fig. 1) is provided to direct a current of air up through the machine to assist in the drying operation.

Extending lengthwise of the machine just above the horizontal run of the conveyor are two stationary horizontal rods 41, 43 (Fig. 3) located in the same horizontal plane and spaced apart a distance greater than the distance between the outsides of the chains 25, 29 of the conveyor so that the conveyor travels between the rods. Referring now to Fig. 1 in which the machine is shown at rest the soles are placed one at a time, in the position occupied by the freshly cemented wet sole 100^A, upon two feed sleeves 45, one of which appears in this figure, the sleeve which appears being slidably mounted on the rod 41 and the other sleeve on the rod 43. When the machine is actuated, this sole is fed to the right in position to be picked up by a pair of fingers 31 which presently move up from below and lift the sole from the feed sleeves 45. At the same time that a freshly cemented sole 100^A is thus fed to the conveyor, a dry sole 100^B, which has been deposited by the conveyor upon the rods 41, 43, is being fed to the right in position to be lifted off the rods and added to the bottom of a stack of dry soles, indicated as a whole at 100^C. This simultaneous feeding of two soles, a wet one 100^A into the path of the conveyor, and a dry one 100^B out of the path of the conveyor results from the simultaneous reciprocation of the pair of feed sleeves 45 referred to above and a second pair of feed sleeves 46 which, like the sleeves 45, are also slidably mounted one on each of the rods 41, 43. Each sleeve 45 carries a wet sole feed member one of which is shown at 47, and each sleeve 46 carries a dry sole feed member one of which is shown at 49. The four feed members are all mounted in the same manner and consequently only the mounting of the member 47 will be described in detail. This member is pivoted at 48 to a bracket 50 carried by the sleeve 45. A tension spring 52 normally holds the feed member in the angular position shown about its pivot 48, the limit of counterclockwise movement being determined by contact of the feed member with a portion of the bracket 50. When the pair of feed members 47 are moved to the right, they push the sole 100^A forward (the feed members 47, as will presently appear, exerting a yielding push) until its leading edge contacts with the chains 25, 29 of the conveyor; and then, while the feed members 47 are still holding the sole against the chains, the sole is lifted by a pair of fingers 31 which presently swing up from below. The feed members 49 for the dry soles, such as the sole 100^B, push the soles along the rods 41, 43 against an abutment, and these soles are then lifted and added to the bottom of the stack 100^C by mechanism presently to be described. After the wet sole 100^A and the dry sole 100^B have been moved up out of the paths of their feed members, these members are moved further forward by their yielding actuating mechanism into the position shown in Fig. 2 before they are returned to their initial positions of rest.

Still referring to Fig. 2 in which the feed members 47, 49 are shown at the limit of their forward movement after the respective wet and dry soles have been removed from in front of them, the mechanism for reciprocating these feed members will be described. The pair of sleeves 45 and the pair of sleeves 46 are both actuated from a forked lever 51, both arms of which are shown in Fig. 3. The base of this forked lever is pivoted to the frame at 53 and carries a roll 55 which runs on a repeating cam 351 mounted on a shaft 57 to which are intermittently imparted half-revolutions. The cam 351 is termed a repeating cam because a plane can be passed through it perpendicular to its plane which will divide it into two symmetrical parts, the action of the cam on the roll 55 for each half-revolution of the shaft 57 being exactly the same. The roll 55 is held against the cam by a tension spring 58 (Fig. 1), one end of which is fastened to the lever 51 and the other end to a pin in the frame of the machine. One of the arms of the forked lever 51 (the left-hand end of Fig. 3) is connected to the feed sleeves 45 and 46 which are slidable on the rod 41, and the other arm of the forked lever 51 is connected to the feed sleeves 45 and 46 which are slidable on the rod 43. Inasmuch as these connections, one set on one side and the other set on the other side of the machine, are the same, only one set of connections will be described in detail. Referring to Figs. 1 and 2, the arm of the forked lever 51 which appears in those figures has pivoted to its upper end at 59 one of the ends of two links 61, 63. To the other end of the link 61 is pivoted at 65 the lower end of a link 67, the upper end of which is pivoted at 69 to a lug on the sole-feeding sleeve 46. A stop screw 71 threaded through the link 67 is normally held in engagement with an abutment on the link 61 by a torsion spring 73 (Fig. 3), said spring being fast at one end to the pivot 65 carried by the link 67 and at the other end to the link 61. The links 61, 67 are thus yieldingly held in the relative positions shown until the feed member 49 has fed a dried sole to the right against the abutment 68 and can move no farther, after which the angle between the two links is increased while the forked lever 51 swings farther to the right. As soon as the sole is removed from in front of the feed member 49, the torsion spring 73 restores the links 61, 67 to the relative angular positions shown, and the feed member 49 moves to the right into the position shown in Fig. 2. The link 63 is pivoted at its lefthand end at 75 to the lower end of a link 77, the upper end of which is pivoted at 79 to a lug on the sleeve 45. A stop screw 81 threaded through the link 77 is held in engagement with an abutment on the link 63 by a torsion spring, not shown, like the torsion spring 73 described above which performs a similar function with respect to the links 61, 67. The connections between the forked lever 51 and the feed sleeves 45, 46 which slide on the rod 41 on one side of the machine have just been described. The connections between the forked lever and the companion sleeves 45, 46 which slide on the rod 43 on the other side of the machine are like those which have been described. The machine comes to rest as has been stated in the position shown in Fig. 1. In the operation of the machine, the operator places a freshly cemented sole 100^A on the feed sleeves 45 and throws in a clutch which imparts a half-revolution to the shaft 57, during which half-revolution the forked lever 51

first swings forward into the position shown in Fig. 2 and then back into the position of rest in Fig. 1.

Referring to Figs. 1 and 2, the mechanism for lifting the dry soles from the rods 41, 43 and stacking them will be described. The stack of soles 100^c is normally supported on two spaced parallel rods 83 horizontally slidable through bores in a part of the frame. The rods 83 have enlarged outer portions having bores parallel to the axes of the rod to receive guide rods 87 carried by the frame of the machine. These enlarged outer portions also have bores extending horizontally at right angles to the axes of the 10 rods to receive cylindrical reduced ends of the T-shaped head (Fig. 3) of a lever 85 which is thus pivoted to the enlarged outer portions of the stack-supporting rods 83. The lever 85 is pivoted at its inner end at 89 to the upper end 20 of a lever 91 the lower end of which is pivoted to the frame at 93, said lever carrying a roll 95 which runs on a repeating cam 391 mounted on the shaft 57. A spring, not shown, like the tension spring 58 (Fig. 1) holds the roll against the cam. Normally held beneath the stack of soles and below the level of the rods 41, 43 (Fig. 1) is a lifter 97 in the form of a fork the tops of the arms of which are located near enough to each other so that the fork may 30 be pushed up between the rods 41, 43 to remove a sole therefrom, said lifter being reciprocated vertically by a lever 99 the forked outer end of which has rolls 101 which engage a spool 103 fast to the stem 105 of the lifter, said stem being vertically slidable in spaced bearings 107 in the frame of the machine. The lever 99 is pivoted at 109 to a rigid part of the machine and carries a roll 111 which runs on a repeating cam 113 which is fast to the shaft 57. A tension 40 spring 114 holds the roll in contact with the cam. The cam 351 which causes horizontal reciprocation of the sole-feeding members, the cam 391 which causes horizontal reciprocation of the stack-supporting rods 83, and the cam 113 which 45 causes vertical reciprocation of the lifter 97 are so shaped and timed that at every half-revolution of the shaft 57, the following movements occur. A dry sole 100^b (Fig. 1) is fed to the right from the conveyor until its leading edge 50 counters the wall or abutment 58. The lifter 97 moves up to lift the sole from the rods 41, 43, and pauses in a position just beneath the stack-supporting rods 83. The rods 83 are then moved to the right from beneath the stack, and the 55 lifter rises farther to a level above that of the rods 83 and pauses a second time. This is the position of parts shown in Fig. 2. The rods 83 are then moved back beneath the stack, and the lifter returns to its position of rest, as shown 60 in Fig. 1.

Any suitable operator-controlled mechanism may be employed for imparting half-revolutions to the shaft 57, and, through these half-revolutions, intermittent movements of proper length 65 to the conveyor. To this end, in the illustrated machine, a Geneva escapement comprising a star wheel 117 (from which the conveyor is driven) and a cooperating pin-member 119 are provided, the pin-member 119 being fast to the cam shaft 57 and carrying on pivots 120 two small rolls 121 which are normally received in adjacent recesses in the star wheel. The pivots of the rolls on the pin-member 119 project from one side of the pin-member, the projecting end of 70 one of these pivots being shown in Fig. 3. When

the machine is at rest (Fig. 1) one of these pivots is engaged by a hook at the upper end of a catch 123 pivoted at 125 to the outer end of a horizontal arm 127, the hub of which is fast to a short rockshaft 129. The catch 123 is held 5 in engagement with a pivot 120 by a small compression spring 131 located in a socket in the arm 127 which acts to swing the catch counterclockwise about its pivot 125, said swinging movement being limited by an abutment on the arm 10 127. Fast to the rockshaft 129, to which the hub of the horizontal arm 127 is fast, is also fast the hub of an upright arm 133 having a roll 135 (Fig. 1^a) which engages a flange on one member 137 of a friction clutch and normally holds 15 said member to the left in inoperative position against the force of a compression spring 139 which tends always to slide the member 137 to the right and thus to throw in the clutch. The member 137 is slidably keyed to a sleeve 141 20 which is fastened to a shaft 143 by a set screw 145, there being threaded into the outer end of the sleeve a screw 147 against the head of which one end of the spring 139 bears. Mounted on the sleeve 141 is a constantly rotating 25 pulley 149 which is connected to the shaft 143 to rotate it whenever the member 137 is permitted to be moved to the right by the compression spring 139. In the position of parts 30 shown, the clutch is being held with its parts disengaged. In order to trip the catch 123 to throw in the clutch, there is pivoted to the lower end of the catch the lower end of a long rod 151, the upper end of which is pivoted to the upper end of an arm 153, the hub of said arm being 35 fast to a rockshaft 155. Also fast to this rockshaft is the hub of a hand lever 157 which is swung to the left by the operator and then released every time he places a freshly cemented sole 100^a on the feed sleeves 45. Swinging the 40 hand lever to the left disengages the catch 123 from the pivot of the roll of the pin-member 119, which it is then engaging, and permits the compression spring 139 (Fig. 1^a) to throw in the clutch. This starts rotation of the shaft 143 45 (Fig. 3) which carries a worm 159 meshing with a worm 161 on the shaft 57 and thereby starts rotation of said shaft 57. The pin-member 119 (Fig. 1), as has been stated, is fast to the shaft 57; and, when this member has made a half-revolution in the direction indicated by the arrow, the pivot pin of the other roll of the pin-member is caught by the catch 123, thereby 50 pulling up the arm 127, swinging the arm 133 to the left and throwing out the clutch. The pin-member, in making this half-revolution, turns the star wheel 117 through an angle determined by the distance between the recesses in its periphery. This star wheel, as has been stated, 55 drives the conveyor. This is accomplished (Fig. 3) by a chain 163 which passes around a sprocket on the hub of the star wheel and a sprocket on the shaft 167 which carries one of the sprockets 23 for the chain 25 and one of the sprockets 27 for the chain 29. 60

The fan 39 referred to above is fast to the upper end of a vertical shaft 171 which carries a pulley 173. Around this pulley, over guide-pulleys 175, 177 and around the left-hand groove (Figs. 1, 1^a) of the driving pulley 149, extends a belt 179. The pulley 149 is continuously driven by a belt 181 from a source of power, not shown. Consequently, the fan 39 is also continuously driven irrespective of whether the clutch shown in Fig. 1^a is operative or inoperative. In order that the 75

5 fingers 31 may be held perpendicular to the chains 25, 29 on the upward and downward runs of these chains, said chains are of the well-known anti-whip type.

10 A brief summary of the operation of the machine will now be given. Assuming that the upward and downward extending runs of the conveyor carry the soles as shown in Figs. 1 and 2, and that the machine has come to rest as shown in Fig. 1, the operator places a freshly cemented sole on the feed sleeves 45 in the position occupied by the sole 100^A, swings the handle 157 to the left and then releases it. Swinging the handle in this manner disengages the catch 123 from the pin-member 119 and permits the compression spring 139 (Fig. 1^a) to throw in the clutch. At the end of a half-revolution of the pin-member 119 and the shaft 57, the catch 123 will engage the other pivot pin on the pin-member so that the arm 127 will be swung up and the arm 133 swung to the left, said latter arm acting to throw out the clutch. During the half-revolution thus imparted to the shaft 57, the following movements will occur. The feed members 47 will feed the wet sole 100^A against the chains 25, 29 of the conveyor. The feed member 49 will feed the dry sole 100^B against the abutment 68. As has been explained there is a resilient drive mechanism for operating these feed members. While the feed members are still being urged to the right, a pair of fingers 31 will lift the sole 100^A from in front of the feed members 47, and the lifter 97 of the stacking mechanism will lift the sole 100^B from in front of the feed members 49 to a point near the stack-supporting rods 83 where it pauses while those rods are moved horizontally from beneath the stack, after which the lifter completes its upward movement. By the time the shaft 57 has made a quarter-revolution, the parts will be in the positions shown in Fig. 2. At the end of the half-revolution of the shaft, they will have returned to the positions shown in Fig. 1.

45 Although the invention has been set forth as embodied in a particular machine, it will be understood that the invention is not limited in the scope of its application to the particular machine which has been shown and described.

Having thus described my invention, what I claim as new and desire to secure by Letters Patent of the United States is:

50 1. A machine of the class described having, in combination, a conveyor provided with article carriers, said conveyor having upwardly and downwardly traveling runs, means for operating the conveyor, spaced supporting rods extending lengthwise of the machine in proximity to the runs, feeding means one for feeding articles to be dried into the path of the carriers and one for feeding dry articles out of the path of the carriers, said feeding means being slidably mounted on the rods, and means for operating said feeding means in timed relation to the operation of the conveyor.

55 2. A machine of the class described having, in combination, a conveyor provided with article carriers, said conveyor having upwardly and downwardly traveling runs, means for operating the conveyor, spaced supporting rods extending from front to rear of the machine in proximity

5 to the conveyor, feeding means slidably mounted on the rods, means for operating the feeding means in timed relation to the operation of the conveyor to feed articles to be dried into the path of the carriers and to deliver dried articles out of said path, a stack support located above the level at which the dried articles are delivered, a stacking member for the dried articles, and means for operating the stack support and the stacking member in timed relation with the feeding means 10 and with each other.

15 3. A machine of the class described having, in combination, a conveyor provided with article carriers mounted in spaced relation thereon, means for operating the conveyor, and yieldingly actuated reciprocating means for pushing an article against the conveyor between two article carriers and for holding it in that position yieldingly until a carrier engages it and carries it away. 20

25 4. A machine of the class described having, in combination, a conveyor provided with article carriers mounted in spaced relation thereon, means for intermittently operating the conveyor, and yieldingly actuating reciprocating means for 25 pushing an article against the conveyor between two article carriers and for holding it in that position yieldingly until a carrier engages it and carries it away..

30 5. A machine of the class described having, in combination, a conveyor provided with article carriers from which articles are fed at one locality, a stack support near said locality, an abutment at a lower level than the stack support, 35 a stacking member movable from a position below the abutment to a position above the stack support, and means for feeding an article away from the conveyor and against the abutment and for holding the article in that position until the stacking member carries it toward the stack support. 40

35 6. A machine of the class described having, in combination, a conveyor provided with article carriers, means for causing the conveyor to travel in a path having upwardly and downwardly extending runs and a substantially horizontal run connecting the bases of the two first runs, supporting means extending substantially parallel to the horizontal run, feeding means one for feeding articles to be dried into the path of the carriers and one for feeding dry articles out of the path of the carriers, and feeding means being slidably mounted on the supporting means, and means for operating said feeding means in timed relation to the operation of the conveyor. 50

45 7. A machine of the class described having, in combination, a conveyor provided with article carriers, means for operating the conveyor, feeding means, means for operating the feeding means in timed relation to the operation of the conveyor to feed articles to be dried into the path of the carriers and to deliver dry articles out of said path, a stack support located above the level at which the dry articles are delivered, a stacking member for the dry articles, and means for operating the stack support and stacking member in timed relation with the feeding means and with each other. 60
